UNITED STATES PATENT OFFICE.

CHARLES LEFEBURE, OF CHILLICOTHE, OHIO.

WATER-BOILING ATTACHMENT FOR GAS-STOVES.

1,083,884.

Specification of Letters Patent.

Patented Jan. 6, 1914.

Application filed March 14, 1912. Serial No. 683,839.

To all whom it may concern:

Be it known that I, CHARLES LEFEBURE, a citizen of the United States, residing at Chillicothe, in the county of Ross and State 5 of Ohio, have invented certain new and useful Improvements in Water-Boiling Attachments for Gas-Stoves, of which the following is a specification.

My invention relates to water boiling attachments for gas stoves and is particularly designed to provide an improved detachable device for a gas stove, which is calculated to utilize the heat normally generated in the oven of the gas stove and to simultaneously 10 be subjected to an independent flame external to the gas stove and desirably playing upon the attachment in such a manner as to insure heating of the water within a comparatively short time and without necessity for starting the main portion of the 15 gas stove into operation.

My invention contemplates the provision of a tank for containing water to be boiled, which may be readily placed in position or 20 which is readily dismountable and which is in such a position with relation to one of the walls of the gas stove oven as to give it benefit of the heating effect of such oven when in operation. As hitherto stated, my 25 invention contemplates the location of such tank in such a manner upon the gas stove and the provision of a heating flame of such a type, that there is provided an auxiliary 30 means for heating the fluid within the tank.

My invention aims to provide such a 35 structure of water heating attachment that initial close proximity to the heated regions of the oven may be attained while, after dismounting of the attachment, the 40 oven structure may be readily rendered complete in the sense that it is not unnecessarily disfigured by its assumption of such a shape as to readily receive the attachment.

The preferred embodiment of my invention is shown in the accompanying drawings, in which similar characters of reference designate corresponding parts, and in which—

Figure 1 is a side elevation of a gas stove 50 with my attachment applied thereto, Fig. 2 is a view in section of the end of a gas stove with my attachment applied thereto, such attachment being shown in section, Fig. 3 is a top plan view of my attachment removed 55 from the gas stove, Fig. 4 is a longitudinal section taken through my attachment, and,

Fig. 5 is a detail view of a slide utilized for completing the formation of the oven when my attachment is removed therefrom.

In the drawings, the stove is shown at 1 60 as mounted upon legs 2 and having an oven 3, which oven, as is the usual construction, is in communication with the flue pipe attachment casting 4 for carrying the products of combustion into the flue through the 65 flue pipe (not shown).

The side or end of the gas stove 1 is desirably provided with brackets 5 and 6 which carry a shelf member 7 having an upwardly extending ridge 8, which shelf is 70 calculated to form a medium of support for the tank 9, being cut away desirably in circular form as at 10. The ridge 8 formed upon this shelf is designed to prevent and effectually prevents movement of the tank 9 75 laterally or longitudinally and the circular aperture 10 preferably comes above a burner 11 fed by a pipe 12 and under the control of a cock 13. This pipe may be held or supported from the shelf by means 80 of a bracket 14 with a supplemental brace 15.

The tank may be of varying structure, but is desirably of substantially rectangular form having its upper end of a slightly 85 greater width than its lower end and provided with a seating rim 16 which supports a superimposed top piece 17 having a downwardly extending flange 18 and provided with a central aperture 19 within which operates a door 20 hingedly mounted as at 21 and having a controlling handle as at 22 and depending ribs 20^a on its two sides and front edges and adapted to seal the door against escape of steam. The edges and seams of this box-like structure are desirably calked with plaster-of-Paris or other suitable material to collect the sweat. There are two important features in the formation of this receptacle and one of these comprises a lateral enlargement 23 formed upon one side of the tank and constituting an integral portion thereof. This lateral enlargement is adapted to extend through an aperture 24 formed in the side of the oven and to 105 thereby partially protrude into the interior of the oven, whereby a portion of the oven heat is transmitted directly through the wall of the tank. The other important feature of my attachment comprises a box-like structure 25 mounted upon one end of the bottom of the shelf 7 and having its outer end 110

closed as at 26, while its inner end is open as at 27. This inner open end 27 is adjacent the heating burner 11 and is calculated, by the natural draft created through the flue 5 structure, to draw the products of combustion from the burner 11 thereinto. The box-like structure 25 desirably extends beyond the end of the shelf member 7 and carries a delivery pipe 28 which preferably extends 10 vertically and then laterally into the oven of the gas stove, as clearly shown in Fig. 2, from whence an exodus for the products of combustion is obtained through the flue structure in any desired manner. The draft 15 from the oven of the gas stove due to the passage of the products of combustion through the flue attachment casting 4 and thence into the flue structure serves to create a draft in the pipe 28 and thereby in turn 20 creates a tendency to the indrawing of the products of combustion from the burner 11.

It will be understood that the essential operations of the gas stove remain the same and that my device is simply an attachment 25 thereto, which is readily removed, but which when in position may be rapidly heated to heat the material contained therein by means of the heat within the oven directly affecting the enlargement upon the 30 side of the tank and by means of the burner beneath the tank and blowing directly upon the bottom of the tank through the aperture 10.

When it is desired to remove my attachment from the oven structure, the tank need 35

only be lifted from its shelf. To facilitate closing of the oven after the tank has been removed, I have provided gateway 29 which are calculated to slidably receive a plate 30. When this plate is in position, the oven of 40 the gas stove is completely closed as far as the aperture 24 is concerned.

It will thus be seen that I have provided a readily detachable water heater for gas stove which may be applied or dismounted 45 without materially interfering with the normal operation of the gas stove.

What I claim, is—

In combination with a gas stove having an oven with an aperture in its side wall, 50 a supporting shelf carried by the side of said oven below said aperture, a tank removably mounted on said shelf, an enlargement on the side of said tank adapted to fit into said opening when the tank is in 55 position on said shelf, a gas jet disposed beneath said tank, a box-like structure having one end carried by said shelf adjacent said gas jet, and a delivery pipe connecting said box-like structure with said oven whereby the products of combustion from said gas jet are conveyed to said oven.

In testimony whereof I affix my signature in presence of two witnesses.

CHARLES X LEFEBURE.
